PORTABLE OR STATIONARY MULTIPLE
AIR JACK

David Terrell Haines, Sr., Dallas, Tex.

Application June 17, 1946, Serial No. 677,284

4 Claims. (Cl. 121—38)

1

The invention relates to a jack, and more especially to a portable or stationary fluid operated jack.

The primary object of the invention is the provision of a jack of this character, wherein through multiple piston or diaphragm action under fluid pressure, either air or water, the said jack will operate for pushing or pulling power, whichever is desired, much greater than would be developed in a larger single unit outfit. The principle is in getting as much pressure area in as small a confined space, as is possible, the jack being of novel construction and unique in the assembly of its parts, which are few in number, thus economical in repairs and replacement of such parts.

Another object of the invention is the provision of a jack of this character, wherein it can be stationary or portable, and compact enough so as in the operation thereof, assures maximum holding power, it being quick acting for gripping and clamping of work in fixtures mounted on machines, benches or otherwise.

A further object of the invention is the provision of a jack of this character, wherein enough power is had for pushing or pulling whatever may be required on a limited line pressure, it being operable with ease and dispatch.

A still further object of the invention is the provision of a jack of this character, which is simple in construction, thoroughly reliable and efficient in operation, strong, durable, positive in the working thereof, assuring a firm and secure grip on work, and inexpensive to manufacture.

With these and other objects in view the invention consists in the features of construction, combination and arrangement of parts as will be hereinafter more fully described, illustrated in the accompanying drawings, which disclose the preferred embodiments of the invention, and pointed out in the claims hereunto appended.

Figure 1 is a side elevation, partly in section of the jack constructed in accordance with the invention.

Figure 2 is a fragmentary bottom end view thereof.

Figure 3 is a sectional view taken on the line 3—3 of Figure 1 looking in the direction of the arrows.

Figure 4 is a sectional view taken on the line 4—4 of Figure 1 looking in the direction of the arrows.

Figure 5 is a slight modification of Figure 1.

Figure 6 is a view similar to Figure 1 showing a further slight modification.

2

Figure 7 is a bottom end view thereof.

Figure 8 is a sectional view taken on the line 8—8 of Figure 6 looking in the direction of the arrows.

Figure 9 is a view similar to Figure 1 showing a still further modification.

Figure 10 is a side view showing a vise with the jack applied thereto.

Figure 11 is a view similar to Figure 10 showing another form of vise and jack application.

Figure 12 is an elevation showing the jack used as a lifting device.

Similar reference characters indicate corresponding parts throughout the several views in the drawings.

Referring to the drawings in detail, particularly Figures 1 to 4, inclusive, which show one form of the jack constructed in accordance with the invention, comprising an elongated cylindrical body 10, having end heads 11 and 12, respectively, these being separable from the body through the medium of internal and external threaded connections 13 therebetween.

Within the end head 11 centrally thereof is slidably fitted a terminal piston 14 which has its tubiform stem 15 extended centrally through the body 10 to the other opposite end head 12. The stem 15 at the said other opposite end head 12 has connection with another terminal piston 16 which is slidably fitted centrally in the said head 12. The piston 16 has a fluid passage 17 leading into the stem 15, and to this passage is connected a fluid conducting hose, only a portion of the same is indicated at 18, of a hydraulic line system, not shown, which involves a two-way valve control set up, which is also not shown, for operating the jack.

Within the body 10 concentric to the stem 15 and longitudinally distributed therethrough is a series or multiplicity of bellows-like hollow expanding and contracting acting elements 19, which are confined within separated chambers 20, created by separator plates or disks 21 and 22, respectively. The plates or disks 21 and 22 within the body 10 are placed concentrically about the stem 15, and the plates or disks 22 are anchored at 23 next to their outer peripheries thereof between spacer collars 24 to the body 10. The collars 24 internally fit the body 10 against the inner wall surface thereof. The plates or disks 21 at their inner peripheries are anchored at 25 between spacer collars 26 which embrace the stem 15, and are fixedly held by the pistons 14 and 16 in assembly with the said stem.

The collars 24 are fixedly held to the body 10 by the heads 11 and 12 in assembly therein.

The chambers 20 outside of the elements 19 are vented by vent holes 21 opening through the said body 10 and the collars 24 fitted thereto, while fluid is admitted and exhausted to and from the elements 19 through registering ports 28, provided in the stem 15 and the collars 26 fitted thereto, so that the fluid is delivered and exhausted through the hose 18 to and from these elements in the working of the jack. 10

The piston 16 has a hanger eye 29, for the attachment thereof to a support, not shown, while the piston 14 is provided with a female coupling extension 30, which is adapted for its separable connection with a piece of work, not shown, to be pushed or pulled by the jack when operating.

The body 10 of the jack can be mounted in a fixed position in any suitable manner on a support therefor, not shown, there being a threaded nipple 31 formed on the head 12 for such purpose.

In Figure 5 of the drawings there is shown a slight modification, wherein the piston 32 which is a substitute for the piston 16 has detachably fitted thereto a holding knob 33, while the piston 34 which is a substitute for the piston 14 has detachably connected thereto a coupling rod, a portion being indicated at 35. In this Figure 5 of the drawings, the body 36 is adapted to be held fixed, while the pistons 32 and 34 move relatively to each other under the influence of the expanding and contracting elements within the body.

In Figures 6, 7 and 8, of the drawings there is shown another modification of the invention, wherein in lieu of the elements 19 there are substituted pistons 37 and 38, respectively, for the plates or disks 21 and 22, heretofore described, and operating within chambers 39 as created thereby between the same within the body 40 of the jack. Also interposed between the end head 41 and the piston 37 next thereto is a coiled compression spring 42, the pistons 37 and 38 carrying packings 43, respectively.

In Figure 10 of the drawings there is shown a vise 44 having a base 45 with a riser 46 into which is fixed horizontally the jack body, while the inside jaw 47 of this vise is stationary, and the outside jaw 48 is movable, the latter being coupled with movable stem of the jack, so that the latter will operate this jaw 48 for the clamping of work by the said vise.

In Figure 11 of the drawings there is shown another form of vise, wherein the outer jaw 49 is stationary, while the inner jaw 50 is movable by the jack.

In Figure 12 of the drawings there is shown a jack assembly hereinbefore described, and denoted generally at 51, for its service as an automobile lift device, yet the latter may be used for other lifting purposes, as should be apparent.

It should be apparent that by reversing the fluid pressure line to the jack a pushing action will be had in lieu of the pulling action as would be the case with the fluid line in the position as now shown in the drawings, namely at the end head 12 in Figure 1 thereof.

What is claimed is:

1. In a multiple air unit jack, the combination which comprises a cylindrical casing having spaced outlet openings therethrough and having threaded ends, heads having centrally disposed hubs with longitudinally extended bores there-

through threaded on the opposite ends of the casing, pistons positioned in the bores of the said heads, a centrally disposed tube having spaced openings through the walls thereof positioned in the casing and on the ends of which the said pistons are mounted, a plurality of spaced annular plates carried by the said centrally disposed tube, extended outwardly therefrom and positioned with the peripheries thereof in sliding engagement with the inner peripheral surface of the cylindrical casing, a plurality of spaced complementary annular plates mounted on the inner peripheral surface of the cylindrical casing and extended inwardly with centrally disposed bores therein in slidable engagement with the said centrally disposed tube and positioned to coact with the plates of the tube to expand the jack longitudinally as fluid under pressure is supplied to areas between the plates, said plates mounted on the cylinder being positioned between the plates carried by the said centrally disposed tube, the said spaced openings of the centrally disposed tube being positioned on one side of the plates carried by the tube and the outlet openings in the cylindrical casing being positioned on the opposite sides of the said plates carried by the tube, and a fluid supply connection in a piston at one end of the centrally disposed tube and communicating with the interior of the tube.

2. In a multiple air unit jack, the combination which comprises a cylindrical casing having spaced outlet openings therethrough and having threaded ends, heads having centrally disposed hubs with longitudinally extended bores therethrough threaded on the opposite ends of the casing, pistons positioned in the bores of the said heads, a centrally disposed tube having spaced openings through the walls thereof positioned in the casing and on the ends of which the said pistons are mounted, a plurality of spaced annular plates carried by the said centrally disposed tube, extended outwardly therefrom and positioned with the peripheries thereof in sliding engagement with the inner peripheral surface of the cylindrical casing, a plurality of spaced complementary annular plates mounted on the inner peripheral surface of the cylindrical casing and extended inwardly with centrally disposed bores therein in slidable engagement with the said centrally disposed tube and positioned to coact with the plates of the tube to expand the jack longitudinally as fluid under pressure is supplied to areas between the plates, said plates mounted on the cylinder being positioned between the plates carried by the said centrally disposed tube, the said spaced openings of the centrally disposed tube being positioned on one side of the plates carried by the tube and the outlet openings in the cylindrical casing being positioned on the opposite sides of the said plates carried by the tube, a plurality of expanding elements positioned between the said coacting plates of the centrally disposed tube and cylindrical casing providing sealing means for areas between the said plates, and a fluid supply connection in a piston at one end of the centrally disposed tube and communicating with the interior of the tube.

3. In a multiple air unit jack, the combination which comprises a cylindrical casing having spaced outlet openings therethrough and having threaded ends, heads having centrally disposed hubs with longitudinally extended bores therethrough threaded on the opposite ends of the casing, pistons positioned in the bores of the said heads, a centrally disposed tube having

spaced openings through the walls thereof positioned in the casing and on the ends of which the said pistons are mounted, a plurality of spaced annular plates carried by the said centrally disposed tube, extended outwardly therefrom and positioned with the peripheries thereof in sliding engagement with the inner peripheral surface of the cylindrical casing, a plurality of spaced complementary annular plates mounted on the inner peripheral surface of the cylindrical casing and extended inwardly with centrally disposed bores therein in slidable engagement with the said centrally disposed tube and positioned to coat with the plates of the tube to expand the jack longitudinally as fluid under pressure is supplied to areas between the plates, said plates mounted on the cylinder being positioned between the plates carried by the said centrally disposed tube, the said spaced openings of the centrally disposed tube being positioned on one side of the plates carried by the tube and the outlet openings in the cylindrical casing being positioned on the opposite sides of the said plates carried by the tube, a plurality of expanding elements positioned between the said coacting plates of the centrally disposed tube and cylindrical casing providing sealing means for areas between the said plates, a fluid supply connection in a piston at one end of the centrally disposed tube and communicating with the interior of the tube, and a spring in the casing positioned between a head at one end thereof and the end plate of the centrally disposed tube at the corresponding end of the jack.

4. In a multiple air unit jack, the combination which comprises a cylindrical casing 10 having spaced outlet openings 27 therethrough and having threaded ends 13, heads 11 and 12 having centrally disposed hubs with longitudinally extended bores therethrough threaded on the opposite ends of the casing, pistons 14 and 16 positioned in the bores of the said heads, a centrally disposed tube 15 having spaced openings 28 through the walls thereof positioned in the casing 10 and on the ends of which the said pistons are mounted, a plurality of spacing collars 24 positioned on the inner surface of the

casing, a plurality of spaced annular plates 21 carried by the said centrally disposed tube, extended outwardly therefrom and positioned with the peripheries thereof in sliding engagement with the inner peripheral surfaces of the spacing collars 24, spacing collars 26 mounted on the tube 15 and positioned between the plates 21, a plurality of spaced complementary annular plates 22 mounted on the inner peripheral surface of the cylindrical casing positioned between the said spacing collars 24 of the casing 10 and extended inwardly with centrally disposed bores thereof in slidable engagement with the said spacing collars on the centrally disposed tube and positioned to coat with the plates 21 of the tube to expand the jack longitudinally as fluid under pressure is supplied to areas between the plates, said plates 22 mounted on the cylinder 10 being positioned between the plates 21 carried by the said centrally disposed tube 15, the said spaced openings 28 of the centrally disposed tube being positioned on one side of the plates carried by the tube 15 and the outlet openings 27 in the cylindrical casing 10 being positioned on the opposite sides of the said plates 21 carried by the tube, and a fluid supply connection positioned in a hub at one end of the centrally disposed tube and communicating with the interior of the tube.
